UNITED STATES PATENT OFFICE.

JAMES M. DILLON, OF BIRMINGHAM, ALABAMA.

VELOCIPED.

SPECIFICATION forming part of Letters Patent No. 325,823, dated September 8, 1885.

Application filed February 12, 1885. (No model.)

To all whom it may concern:

Be it known that I, JAMES M. DILLON, of Birmingham, in the county of Jefferson and State of Alabama, have invented a new and Improved Foot-Power for Velocipedes, &c., of which the following is a full, clear, and exact description.

This invention relates to certain new and useful improvements in the driving or working of velocipedes—such as tricycles, quadricycles, &c.—either for railways or ordinary roadways.

The invention consists in arrangements and combination of parts and details, as will be fully described hereinafter, and pointed out in the claims.

Reference is to be had to the accompanying drawings, forming part of this specification, in which similar letters of reference indicate corresponding parts in all the figures.

Figure 1 is a longitudinal sectional view of my improved velocipede. Fig. 2 is a plan view of the same. Fig. 3 is an enlarged side view of the ratchet on a belt-pulley. Fig. 4 is a plan view of the swinging ends of the foot-levers. Fig. 5 is a rear end view of the steering-wheel and part of the frame.

The two driving-wheels A are rigidly mounted on the ends of axle B, and adjacent to the inner end of the hub of each wheel the end of a side shank of a U-shaped frame, C, is hung, which frame C has an upwardly projecting part, D, in its rear cross-piece, into the top of which part D a pin, F', passes from the top of a fork, F, in which the rear steering-wheel, G, is journaled, the part D being of sufficient width to permit the steering-wheel G to turn.

A fork, H, projects toward the front from the lower ends of the fork F, and a pin or pivot, H', on the front end of the fork H passes loosely through a block, J, arranged to slide on a transverse bar, K, uniting the side pieces of the frame C.

The ends of a wire, L, are secured to the sides of the block J. The wire is passed over pulleys J' at the ends of the bar K and over pulleys on the ends of a cross-bar, M', held above the axle on standards M on the upper or front ends of the side bars of the frame C.

A ball or other handle, N, is secured on the

wire L in front of the bar M'. On the axle B a double ratchet-wheel, O, is rigidly mounted—that is, a wheel with two ratchet-rings—and adjacent to each side of the ratchet-wheel a disk or pulley, P, is loosely mounted on the shaft or axle B. On the inner side of each pulley or disk P a sliding bolt, Q, is arranged, the inner beveled end of which is pressed upon the corresponding ring of ratchet-teeth by a spring, Q'; or, in place of the said bolt, any other spring-pawl may be provided.

At each side of the part D a foot-lever, R, is pivoted on the rear cross-piece of the frame C to swing vertically, the points or swinging ends of the said levers being below the axle or shaft B. One lever, R, is provided at its front or swinging end with the two prongs r' r', and the other with the prong r'', adjusted to pass between the prongs r' r'.

Over each disk or pulley P, which is grooved, a metal band or belt, S, is passed, which is secured at the middle of its length to the rim of its pulley P.

The front end of one band S—that is, the end of the part extending down in front of the axle—is secured on the prong r' of one lever R, and the other end, or the rear part of the band extending down behind the axle, is secured to the prong r'' of the other lever R. The other band S has one end secured to the prong r' of one lever R, and the other end to the prong r'' of the other lever R, as shown in Fig. 4. A brake-block, T, is held by a spring, U, above the rim of one wheel A, the said spring U being secured on one standard M.

In place of the brake shown, a brake-lever pivoted on one standard M, or any other brake, may be used.

For use on railways flanged wheels are used, and in place of the steering-wheel two rear wheels are used.

The above-described driving mechanism can be used for operating lathes or other machinery or for other purposes.

The operation is as follows: The operator places his feet on the treadles or foot-levers R and depresses them alternately. When a lever is pressed down, the front part of a band, S, is pulled down and turns the corresponding disk or pulley, P, in the direction of the arrow a', and as the bolt or pawl Q is engaged with

the ratchet-wheel O the said ratchet-wheel and the axle are revolved in the direction of the arrow a' . At the same time the rear part of the said belt raises the other lever R, with which it is connected. The bolt Q or pawl of one pulley P turns the ratchet-wheel, and at the same time the opposite teeth of the ratchet-wheel slide under the bolt or pawl on the other pulley P. Then the bolt or pawl of the latter pulley revolves the axle, and then the bolt or pawl of the first-mentioned pulley revolves the axle, and so on.

To steer the velocipede, the ball N is shifted to the right or left, whereby the steering-wheel is turned.

To apply the brake, the band is placed on the block T and the said block pressed upon the rim of the wheel.

Having thus described my invention, what I claim as new, and desire to secure by Letters Patent, is—

1. The combination, with a shaft, of a ratchet-wheel mounted rigidly on the same, pulleys mounted loosely on the shaft and having pawls or bolts for engagement with the teeth of the ratchet-wheel, bands secured on each pulley, and two foot-levers, each of the above-described bands having one end secured on the free end of each foot-lever, substantially as herein shown and described.

2. The combination, with a shaft, of the double ratchet-wheel O, the pulleys P, having bolts Q or pawls, the bands S, secured on the

rims of the pulleys, and the foot-levers R, of which one has the prongs r r' and the other the prong r^2 , the bands S each having one end secured to the prong r^2 , and the other end to the prong r or r' , substantially as herein shown and described.

3. In a velocipede, the combination, with the driving-wheels and a frame hung on the axle, of a steering-wheel journaled in a fork pivoted in the rear cross-piece of the frame, a block running on a cross-piece of the frame and connected with the fork of the steering-wheel, and a wire connected with the said sliding piece and running along a bar above the axle, which wire has a ball or handle piece, substantially as herein shown and described.

4. In a velocipede, the combination, with the driving-wheels and a frame hung on the axle, and having a raised part, D, on its rear cross-piece, of the fork F, pivoted on the part D, the wheel G in the fork F, the fork H, the cross-bar K, the sliding block J on the same, the pin H', projecting from the fork H through the block J, and the wire L, secured to the block J and passed in front of a bar above the axle, substantially as herein shown and described.

JAMES M. DILLON.
